FLUID OPERATED CONTROL SYSTEM

Joseph J. Slomer, Chicago, Ill., assignor to Goodman Manufacturing Company, Chicago, Ill., a corporation of Illinois

Application January 14, 1944, Serial No. 518,245

12 Claims. (Cl. 172—179)

1

This invention relates to improvements in fluid operated control systems particularly adapted to control the electric circuits of motors used to propel mine locomotives.

Heretofore controllers of the fluid operated and mechanical and electrically operated types have been so arranged that upon overload of the motor circuit all of the contactors open at one time. This creates a heavy arc that cannot adequately be extinguished, and thus causes excessive burning of the contacts of the controller.

One of the principal objects of my present invention is to overcome this excessive arcing and burning of the contacts by providing a novel form of fluid operated controller for a motor circuit, having a fluid pressure release of a novel construction, electrically connected with the motor circuit, and so connected in the fluid control system as to release fluid therefrom upon overload of the electric circuit, in such a manner that the electric contacts, closing the electric circuit, will open step by step in a predetermined order.

Another object of my invention is to provide a novel and efficient form of fluid release valve electrically connected in the motor circuit so as to release fluid from the system upon overload of the locomotive circuit.

Still another object of my invention is to provide a fluid operated controller including a novel form of control valve for supplying fluid to control opening and closing of the contactors at pressures increasing or decreasing step by step, to successively open or close the electrical contacts of the control system.

A further object of my invention is to provide a new and improved form of fluid control valve and fluid operated control system adapted to positively operate a plurality of devices in a regular sequence or order.

A prior application Serial No. 488,015, filed by William W. Sloane on May 22, 1943, which is a division of application Serial No. 456,490, filed on August 28, 1942, which issued as Patent No. 2,383,894 on Aug. 23, 1945, relates to a fluid operated control system somewhat similar to that shown in my present invention. My present invention, however, differs from that disclosed in the prior application of William W. Sloane in the form of control valve for supplying fluid at pressures increasing or decreasing step by step, to operate the contactors for closing the electric circuit, and in the form of release means for releasing fluid under pressure from the system upon overload of the electric circuit.

Other objects of my invention will appear from

2

time to time as the following specification proceeds and with reference to the accompanying drawings wherein:

Figure 1 is a diagrammatic view illustrating an electrical control circuit for the motors of an electrical device, such as a locomotive, and showing the fluid circuit for controlling operation thereof;

Figure 2 is a fragmentary plan view of a variable pressure control valve constructed in accordance with my invention, with certain parts of the valve broken away and certain other parts shown in horizontal section;

Figure 3 is a fragmentary view in side elevation of the valve shown in Figure 2, with certain parts broken away and certain other parts shown in longitudinal section;

Figure 4 is a detail horizontal sectional view taken through the valve illustrating certain details of the interlock for interlocking the variable pressure control valve with the valve for controlling reversal of the locomotive;

Figure 5 is an end view of the control valve with certain parts thereof shown in transverse section in order to show certain details of the valve;

Figure 6 is a detail transverse sectional view of the valve showing certain details of the manually controllable emergency valve, for releasing fluid from the fluid pressure system;

Figure 7 is a transverse sectional view taken substantially along line 7—7 of Figure 2;

Figures 8 and 9 are enlarged detail sectional views of the variable pressure control valve, showing said control valve in closed and open positions respectively;

Figure 10 is a detail view of the control valve, showing certain details of the fluid connections thereto;

Figure 11 is a plan view of the release valve with certain parts thereof shown in horizontal section; and

Figure 12 is a longitudinal sectional view taken through the valve shown in Figure 11.

For the purposes of illustrating my invention, Figure 1 of the drawings diagrammatically shows an electric control circuit particularly adapted to control the simultaneous operation of a plurality of electric motors 10, 10, preferably the motors 50 of a mine locomotive, together with a hydraulic control system arranged in accordance with my invention, for controlling the operation of the electrical contacts of this control circuit. Said motors are herein shown as being connected in parallel for simplicity, it being understood that

the electric control circuit may be so arranged as to connect said motors in series or in series parallel, or in any other desired manner. Starting and stopping of said motors is controlled by a plurality of fluid operated contactors 1, 2, 3, 4, 5, 6, 7 and 8, contained in a suitable control box (not shown) and arranged to connect the motors to a main power line 11 and to progressively cut sections of a resistance 12 into or out of the motor circuit.

A fluid pump 13, driven by an electric motor 14, is provided to supply pressure for the system. Said pump is supplied with fluid from a suitable tank, herein shown as being the low pressure side of an accumulator 15, by means of a pipe 16. Said accumulator serves as a fluid storage tank for the hydraulic system and may be of any well known form, and is herein shown as including a tank 17 having a cover 19. Said cover is provided with an inwardly extending cylindrical piston 20 extending within and opening into said tank and having a cylinder 21 slidably movable therealong. The inner end of said cylinder is closed and a flanged portion 23 of said cylinder is adapted to abut the inside of said cover 19 when said cylinder is in a retracted position. A pair of concentrically arranged compression springs 24 and 25 are interposed between the bottom of said tank and the inside of said flange 23 of said cylinder, to urge said cylinder into a retracted position.

A pipe 26 having a check valve 27 therein connects the pressure side of the pump 13 with the pressure side of the accumulator 15, to supply fluid under pressure thereto, to cause the cylinder 21 to move against the compression springs 24 and 25. The strength of the springs 24 and 25 is such as to accumulate fluid under pressure in said piston and cylinder and to supply fluid to the system at the required pressure whenever said fluid pump is out of operation, or at a pressure much higher than the capacity of said pump, where necessary.

The electric motor 14, which drives the pump 13, is controlled by a fluid operated switch 30. Said fluid operated switch may be of any well known form and is no part of my present invention, so is not herein shown or described in detail. Said switch is so arranged that when pressure in the pipe 26 reaches a predetermined value, a piston 31 in a cylinder 32 will be moved in a direction to open the electric circuit to the motor 14, and when fluid pressure in said pipe drops below this predetermined value, said switch will close. The operating pressure at which said switch closes is determined by the springs 24 and 25 in the accumulator 15.

A pressure pipe 36 leads from the high pressure side of the accumulator 15, to a valve 37, for controlling operation of fluid brakes 38, 39 for the locomotive, in a well known manner. Said valve and brakes are no part of my present invention, so are not herein shown or described in detail.

A pressure pipe 39 leads from the pressure pipe 36 to a variable pressure control valve indicated generally by reference character 40. Said variable pressure control valve is adapted to supply fluid under pressure to a distributor valve 41, which is connected with the contactors 1 to 8 inclusive for operating said distributor valve and said contactors in a predetermined order.

A control handle 42 on a vertical shaft 43 is provided to operate the variable pressure control valve 40. When said control handle is turned in

one direction, fluid under pressure will be supplied to the distributor valve 41, through a pipe 44, relief valve 45, and a pipe 46, at pressures progressively increasing step by step, and when said control handle is turned in an opposite direction, fluid will be released from said distributor valve at pressures progressively decreasing step by step, as will more clearly appear as this specification proceeds.

10 Fluid under pressure is admitted to the variable pressure control valve 40 through a poppet valve 47 mounted in a block or casing 35 for said variable pressure control valve. Said poppet valve is urged into a closed position by fluid entering said 15 valve through the pipe 38 and by a coil spring 48. A rocking arm 49 is provided to open said poppet valve. Said rocking arm is pivotally mounted on a vertical shaft 51 at one of its ends and has engagement with the projecting end of a stem 50 20 of said valve, intermediate its ends. The opposite end of said rocking arm is bifurcated and has a roller 52 mounted between the furcations thereof on a pivotal pin 53 (see Figure 3). Said roller is adapted to engage a notch 54 in a notching cam 25 55, or any one of a plurality of spaced notches 56, 56 in said notching cam. When said roller is in engagement with the notch 54, said valve will be in an off position. When, however, said roller rides out of said notch and into engagement with 30 the notches 56, 56, effected by pivotal movement of said notching cam, said rocking arm will serve as an index, indexing the positions of the control handle 42 for certain predetermined pressures admitted to the pipe 44 and distributor valve 41 35 through the variable pressure control valve 40, it being understood that since the notches 56, 56 are not as deep as the notch 54, said valve will be in an on position when said roller is in engagement with said notches 56, 56. Said index is 40 herein shown as being formed integrally with a sleeve 57 keyed on the vertical shaft 43 and journaled in the casing 35 for the control valve.

As the control handle 42 is turned to an on position, to cause the roller 52 to ride out of the 45 notch 54 and into the first notch 56, or into any one of the succeeding notches 56, 56, fluid under pressure will be admitted to the valve block through the poppet valve 47 to the variable pressure control valve 40 through a passageway 58, and will also be admitted to a passageway 59 leading to a manually operated emergency release valve 60 (see Figure 1).

The release valve 60 is normally in a position, which in Figure 1 is shown as being an up position, 55 to admit fluid under pressure to a reverse valve 61 in the valve casing 35, which controls reversal of the motors 10, 10. Said release valve, as herein shown, includes a land 62 on the inner or lower end of a piston 63. When said land and piston 60 are in the position shown in Figures 1 and 6, fluid under pressure will pass through the barrel of said valve and out a passageway 64 leading to the reverse valve 61. When the land 62 is depressed by the exertion of pressure on a hand grip 65 of 65 said valve, a land 630 of said valve will block the passageway 59 to hold pressure in the line 39 so the hydraulic brakes 38 or other hydraulic devices of the locomotive may be operated. When said valve is in this depressed position, fluid pressure 70 will be released from the reverse valve 61 to the return through the passageway 64, to and through a passageway 66 in the barrel of said valve and into the valve casing through a passageway 67. Fluid will then pass out of said casing through a 75 passageway 68 leading to a return line 34, and

through said return line to the low pressure or tank side of the accumulator 15. A well known form of ball type spring-pressed detent 69 is provided to hold said control valve in either an open or closed position.

The reverse valve 61 includes a plunger 70 slidably mounted in the valve casing 35. Said plunger, as herein shown, has an integrally formed land 71 at its lower end, an integrally formed land 72 spaced upwardly therefrom, and a third integrally formed land 73, spaced upwardly from said last mentioned land. The lands 71 and 72 are adapted to control the admission and release of fluid to the head end of a reversing cylinder 14, having a piston 75 slidably mounted therein. The lands 72 and 73 are adapted to control the admission and release of fluid to the piston rod end of said cylinder. Said piston 75 has a projecting piston rod 150 which has connection with an arm 751 extending from a reverse drum 76, for pivotally moving said reverse drum in one direction or another, to reverse the direction of the flow of current through the motors 10, 10 and to reverse the direction of rotation of said motors in a well known manner.

The reverse valve 61 is operated by a handle 77 on the upper end of a shaft 78 journaled in the casing 35. Said vertical shaft has a spool-shaped lower portion 79, herein shown as being formed integral with its lower end, which has the plunger 70 of said reverse valve extending between the flanges thereof. A pin 80 is mounted at its ends in the flanges of said spool-shaped portion and has slidable engagement with a slot 81 formed in said plunger 70. Said slot extends in an angular direction with respect to the longitudinal axis of said plunger from the center of said plunger towards the outer end thereof and opens to one side thereof. Thus, operation of said valve handle 77 to pivot the shaft 78 in one direction or another, will slidably move said plunger along its longitudinal axis in the valve casing 35, to slidably move the lands 71, 72 and 73 in directions to cover and uncover certain ports in said valve casing, to supply fluid under pressure to one end or the other of the cylinder 14, and to release it from the opposite end of said cylinder (see Figure 4).

An interlocking means is provided to prevent operation of the reverse valve 61 when the control valve 40 is in an on position, and vice versa. Said interlocking means, as herein shown, includes a plunger 83 slidably mounted in the valve casing 35 for movement along its longitudinal axis in a direction transverse to the direction of movement of the plunger 70 (see Figure 3). Balls 84, 84 abut opposite ends of said plunger 83. One of said balls 84 is adapted to ride in either one of a pair of grooves 85, 85 formed in the plunger 70. The opposite ball is adapted to engage a notch 86 formed in a disk 87, which is secured to the lower end of the control shaft 43. When said control shaft 43 is positioned so that the variable pressure valve 40 is in an off position, one ball 84 will ride in the notch 86, formed in the disk 87, permitting the opposite ball 84 to pass out of either of the grooves 85, 85 to permit free movement of the plunger 70. When said reverse valve is in an intermediate position the ball 84 engaging a notch of the disk 87 will lock said disk and the control shaft 43 from movement, and will prevent operation of the variable pressure control valve. When said reverse valve is in either a forward or reverse position, the associated ball 84 may fall into either one of the grooves 85, 85

to permit the opposite ball 84 to ride out of the notch 86 and to permit operation of the control shaft 43, it being understood that upon operation of said control shaft, the outer periphery of the disk 87 will positively engage a ball 84 with either of the grooves 85, 85, to lock said plunger and reverse valve from movement.

When the plunger 70 of the reverse valve 61 is in the extreme position shown in Figure 1, fluid under pressure will pass from the release valve 69 through the passageway 64 into the valve chamber. It will then pass through the space between the lands 71 and 72 of said valve, through a pressure pipe 88, to the head end of the cylinder 14, to move the piston 75 in a direction which, as shown in Figure 1, is to the left. This will connect the motors 10, 10 to operate in one direction through the reverse drum 76, in a manner well known to those skilled in the art and not herein shown or described since it is no part of my present invention. Movement of said piston 75 within said cylinder to one extreme position or another will uncover a port 89 in said cylinder leading to a pressure pipe 90. Said pressure pipe is connected with the distributor valve 41, for supplying fluid under pressure to the contactors 1 to 8, inclusive, as the ports in said distributor valve leading to said contactors, are opened.

When the reverse valve 61 is in the position just described, fluid will be released from the piston rod end of the cylinder 14, through a pipe 93 connected with said reverse valve. Fluid will pass through the chamber of said reverse valve between the lands 72 and 73 and out through the passageways 67 and 68 to the return pipe 34.

When the plunger 70 has been moved in an opposite direction, by operation of the control handle 77, the land 72 will be moved to a position to allow fluid to flow from the pressure passageway 64 through the pipe 93 to the piston rod end of the cylinder 14. This will move the land 71 to a position to connect the pipe 88 to the return through a passageway 94, to release fluid pressure from the head end of the cylinder 14. The application of fluid under pressure to the piston rod end of said piston will turn the reverse drum in a direction to reverse the direction of rotation of the motors 10, 10 in a well known manner, and will permit fluid pressure to pass through the cylinder 14 and out the port 89 and pipe 90, to the distributor valve 41.

The distributor valve 41, diagrammatically illustrated in Figure 1, includes a cylindrical chamber 95 having a piston 96 movable therein. Said piston, as herein shown, has three spaced apart lands 97, 98 and 99, formed integrally therewith, the land 97 being at the end of said piston, adjacent the inlet from the control pipe 46, so that fluid under pressure entering said valve from said pipe will move said piston against a coil spring 100, interposed between the inner end of said chamber and the end of said piston opposite from the land 97.

A drain passageway 101 is provided in the body of the chamber 95 and leads to the return pipe 34, to take care of any leakage of fluid past the lands 97 or 98. Another drain passageway 102 is provided in the body of said chamber. Said passage leads to the return pipe 34 and is provided to take care of any leakage of fluid past the land 99, and serves as a return for fluid released from the cylinders for operating the contactors 1 to 8, inclusive.

The pressure pipe 96 enters the distributor valve 41, intermediate the ends thereof, at a

point disposed adjacent the end of the land 99 which faces the land 98, when the spring 100 is extended, as in Figure 1. The lands 98 and 99 are so spaced that fluid under pressure will be supplied in the space between said lands in all positions of the piston 96 in the cylindrical chamber 95. It should be noted that fluid admitted from the pipe 90 acts equally in opposite directions on the piston 96, in the space between the lands 98 and 99, so has no tendency to move said piston in the direction of its axis.

Pipes 103, 104, 105, 106, 107 and 108 are connected with suitable port openings or passageways in the chamber 95 at points disposed on the opposite side of the land 99 from the lands 97 and 98, when the piston 96 is in an extreme off position. Said pipes are so arranged that the respective passageways connecting said pipes to the chamber 95 will be successively uncovered by the land 99, to progressively admit fluid under pressure from the pipe 90 to said pipes 103, 104, 105, 106, 107 and 108, upon movement of the piston 96 against the spring 100. Thus, as the piston 96 moves to successively uncover the passageways connected with the pipes 103 to 108, inclusive, fluid will be supplied to the motors for operating the contactors associated therewith, to close said contactors in a predetermined sequence. This will connect the motors in the main line circuit and cut the resistance 12 from the motor circuit step by step under control of the operator.

The strength of the spring 100 is such that the piston 96 will move a distance sufficient to cause the land 99 to open the passageway connected with the pipe 103 to fluid under pressure from the pipe 90, when fluid enters the end of the chamber 95 from the pipe 46 at a predetermined pressure, and will open the next passageway to fluid under pressure from the pipe 90, when fluid pressure on the land 97 of said piston increases a predetermined amount, and so on, until all of the passageways are opened step by step. Upon reducing the fluid pressure entering the chamber 95 from the pipe 46, the spring 100 will move the piston 96 in a reverse direction to successively close the passageways leading from the pipes 108, 107, 106, 105, 104 and 103, to pressure from the pipe 90 and to open said passageways to the drain 102, to release fluid under pressure from the contactors 1 to 8 inclusive in a predetermined order, and to disconnect the locomotive motors from the source of power.

Referring now in particular to the variable pressure control valve 40, which supplies fluid under pressure to the distributor valve 41 through the control line 44, relief valve 45, and control line 46, at uniformly increasing or decreasing pressures, which change step by step for each port opening of said distributor valve as the control handle 42 of said valve is turned by the operator in one direction or another, said control valve is especially designed to maintain substantially the same pressures on the control line at the same position of the control handle, when said control handle and valve are turned in either an on or an off direction.

The control valve 40 is of the piston type having a piston 109 movable in a sleeve 110, mounted in the valve casing 35. The variation in pressure resulting from said piston valve as it is admitting fluid from a lower to a higher pressure and from a higher to a lower pressure, is independent of pressure in the intake pressure line 58 and is due to the lap of the piston or

to mechanical differences only. In order to reduce the lap of the piston and the mechanical differences to a minimum and thus reduce this variation in pressure for the same positions of the control handle as it is turned in an on or an off direction, said piston is provided with three lands 111, 112 and 113, adapted to register with corresponding lands formed in the inner periphery of the sleeve 110, thus providing a multiple lap piston for controlling the admission of fluid to the control line 44. Said piston is drilled along its longitudinal axis from the left-hand end thereof for a portion of its length, and is cross drilled as indicated by reference character 114 at the left-hand end of the land 111, to permit fluid under pressure to pass through the left-hand end of said piston, to and through the pressure line 44. A compression spring 115 extends within the drilled portion of said piston and tends to urge said piston in a direction to the right. Said piston is likewise provided with three lands 118, 119 and 120 adjacent its right-hand end, which control the discharge of fluid to the return. The provision of the multiple lands 111, 112, and 113, and 118, 119 and 120, registering with corresponding lands formed in the inner periphery of the sleeve 110, makes it possible to reduce the lap of the piston so that pressure will be admitted or discharged by said piston with a very slight movement of said piston within the valve sleeve. This will reduce the inaccuracies of said valve due to mechanical differences, and will make the valve sufficiently accurate to insure full and accurate opening and closing of the ports in the distributor valve 41 for the same positions on the control handle 42, when said control handle is being turned in an on or an off direction.

The valve 40 is operated by a pair of spaced gears 123, 123, herein shown as being formed integrally with the control shaft 43. Said gears mesh with racks 124, 124 cut on spaced upper and lower inner ends 125, 125 of a valve operating member 126 (see Figure 7). Said valve operating member is of a substantially C-shaped formation with the racks 124, 124 cut integrally with the upper and lower inner ends thereof, and has a sleeve 127 mounted therein and abutting a closed end 128 thereof (see Figure 3). Said closed end 128 of said valve operating member is slidably mounted on a hollow pilot 129. A hollow piston 130 is mounted on said pilot for movement therewith and extends within said sleeve 127 and is concentrically spaced therefrom. Said hollow piston has an enlarged inner portion which fits snugly within and is secured at its inner end to an inwardly flanged portion of said sleeve 127, as by welding. A compression spring 133 extends within said valve operating member, between the inside of the sleeve 127 and the outside of the hollow piston 130, and is seated at one of its ends in said sleeve and piston. The opposite end of said compression spring abuts and is seated in a seat 134, freely mounted on the inner or right-hand end of the piston 109. The connection between said seat and the valve piston is relatively loose, to avoid binding between said seat and piston and to cause an even pressure to be exerted on said piston by said spring at all times. The pilot 129 is cross drilled adjacent its outer or right-hand end and the passageways formed by said cross drilled portion communicate with a passageway 135, leading to a passageway 136, communicating with an annular groove 137 formed in the outer periphery of the valve sleeve

110. Said sleeve is cross drilled from said annular groove into the inside thereof, to permit fluid under pressure to enter said groove 137 through said cross drilled passageways and to pass through the passageways 136 and 135 to and through the hollow pilot 129. Fluid passing through said passageways may thus exert pressure on the inside of the hollow piston 130, to balance the pressure of the spring 133 so the control handle 42 can be operated with a minimum amount of effort and so said control valve will stay in any desired position for which it is set, without being held by the hand. At the same time pressure is exerted on the inside of the hollow piston 130, fluid under pressure passes through the cross drilled passageways 114, to exert pressure on the left-hand end of the valve piston 109 substantially equal to the pressure exerted by the spring 133.

When the valve 47 has been opened by the rocking arm 49 by turning the control handle 42 to an on position, fluid under pressure will enter the passageway 58, which communicates with an annular groove 139 formed in the outer periphery of the valve sleeve 110. Said valve sleeve is cross drilled from said grooved portion 139 to the inner periphery thereof, as in indicated by reference characters 140, 140, to permit fluid to pass from the passageway 58 to the valve piston 109 (see Figures 8 and 9).

When the valve 40 is in the position shown in Figure 8, the spring 133 will be free and there will be a predetermined amount of clearance between the end of said spring and the seat 134. In this position of said valve, the land 111 will close the passage of fluid to the control line 44 and there will be no pressure in said control line. As the control handle 42 is turned in a direction, which in Figure 3 is a clockwise direction, the valve 47 is first opened to admit fluid to the valve piston 109, as has been mentioned before. The spring 133 at the same time is moved to the left into engagement with the seat 134. Continued turning of said control handle will compress said spring and cause said spring to move the piston 109 to the left until the land 113 is moved out of lap with the corresponding land formed in the valve sleeve 110, as is shown in Figure 9. This will admit fluid within the valve sleeve 110 and will permit fluid to pass by the land 113 into a groove 138 formed in the valve sleeve. From thence fluid will pass in the space between the lands 113 and 112, into a groove 141 formed in said valve sleeve, into the space formed between the lands 112 and 111, into a groove 142 formed within said valve sleeve, through the cross drilled passageways 114, 114 to the hollow center of said valve, and through the hollow center of said valve out through the control line 44 to the distributor valve 41. At this time fluid will also be exerted against the left-hand end of said piston, to tend to move said piston to the right against the compression spring 133.

When the pressure exerted against the left-hand end of the piston 109 is greater than the pressure exerted against said piston by the spring 133, said piston will move to the right against said spring. When said piston has been moved to the right a distance sufficient to move the land 118 out of lap with the inside of the valve sleeve 110, fluid will be discharged through cross drilled passageways 143, 143, through a groove 146 formed within the sleeve 110 in the space be-

tween the lands 118 and 119, through a groove 147, formed within the valve sleeve 110 in the space between the lands 119 and 120, through a groove 149 formed in said sleeve, and through passageways drilled from the inner end of said sleeve into said groove, to the hollow chamber formed in the casing 35, and out through the discharge passageway 68 to the low pressure side of the accumulator 15.

10 When the control handle 42 is turned to the first operating position, the spring 133 is displaced an amount equal to the travel of the operating member 126 minus the clearance between the end of the spring and the valve seat and the clearance 15 between said valve seat and the end of the valve cylinder 110. When said spring has been displaced this amount, fluid under pressure will pass through the hollow piston 109 into the chamber leading to the control line 44, at a pressure substantially equal to the force exerted by the spring 133. This pressure is sufficient to move the piston 96 and land 99 of the distributor valve 41 to a position to open the first port opening to fluid under pressure from the pressure line 90, to supply fluid under pressure to close the contactors 1 and 8 (see Figure 1). As pressure in the control line 46 tends to increase beyond the force exerted by the spring 133 and the valve required to open the first port opening in the distributor 20 valve 41, the valve piston 109 will be moved to the right against the spring 133 by pressure exerted against the left-hand end of said piston, to release fluid from the end of the valve sleeve 110 into the hollow casing 35. As the pressure 25 against the left-hand end of said valve piston is reduced, said spring 133 will move said valve piston to the left a distance sufficient to close the passage of fluid from the passageway 58 to the line 44. If the pressure tends to be reduced below the value required to hold said distributor 30 valve open at the first port opening, said spring will move said piston a distance sufficient to admit fluid under pressure past the lands 111, 112 and 113, to the control line 44.

45 It should here be understood that in order to maintain the desired pressure in the control line 44 and take care of any leakages of fluid, the piston 109 is continually moving back and forth in the valve sleeve 110, to hold pressure in the line 44 and admit fluid under pressure to said line, or to discharge fluid from the end of the sleeve 110 to the hollow inside of the casing 35 and to the return through the passageway 68.

50 As the displacement of the spring 133 is increased by turning of the control handle 42 in a clockwise or on direction, the pressure of the fluid entering the control line 44 will be correspondingly increased. Thus a definite pressure will be supplied to the distributor valve 41 for each notch 55 on the notching cam 55, which pressures progressively increase step by step, to successively open the port openings in the distributor valve 41 to the passageways 103, 104, 105, 106, 107 and 108. When all of the passageways 103 to 108 inclusive 60 are opened, all of the contacts 1 to 8 will be closed and the motors 10, 10 will be in a full speed running position.

65 As the control handle 42 is turned in an opposite direction, the displacement of the spring 133 will be decreased for each step on the notching cam 55 and fluid pressure exerted against the left-hand end of the valve piston 109 will move said valve piston to the right. This will permit fluid to be discharged through the return passageway 68, until said valve piston has been bal-

anced and the desired pressure has been established in a control 46 for the corresponding position of the control handle 42, so the contactors 1 to 8 will open in a predetermined order.

Referring now in particular to the relief valve 45 which forms an overload relay for the electrical system, said relief valve, as herein shown, includes a valve piston 153 slidably mounted in a chamber 154 formed in a valve block 155. A compression spring 156 encircles a reduced end 157 of said valve piston and abuts the end of a land 159 of said piston. The opposite end of said spring abuts the closed end of a threaded sleeve 160, threaded within an enlarged drill hole formed in the end of said valve block, concentric with the chamber 154. A nut 161 and threaded cap piece 162 are provided to lock said threaded sleeve in position and to hold said spring to the desired tension.

The opposite end of the valve piston 153 abuts an armature 163 slidably mounted in a sleeve 164, secured to and extending outwardly from the valve block 155, concentric with the chamber 154. Said armature is encircled by a shunt coil 165 and a series coil 166, spaced outwardly from said shunt coil. Said shunt coil serves as a holdout coil, to hold said relay in a discharge position until the power circuit is interrupted, and is shown in Figure 1 as being connected with a switch 169, which is connected with a positive conductor 170 of a main power line.

The series coil 166 is connected in series with the main line circuit leading to the motors 10, 10, and serves to move said armature in a direction, which in Figures 11 and 12 is shown as being to the left, upon a predetermined load on the motor circuit. It should here be understood that the shunt coil 165 is connected in the motor circuit when the switch 169 is closed, and that said coil serves only as a holdout coil, to hold the valve in a discharge position, when it has been opened by the series coil, due to a predetermined load on the motors 10, 10. When it is desired to reset the relay, the switch 169 is opened to interrupt the power circuit to the shunt coil 165. The spring 156 will then return the valve piston 153 to a position to permit fluid under pressure to flow through said release valve from the control line 44 to the control line 46. Said switch is then closed to supply power to said shunt coil, it being understood that said shunt coil is not strong enough to actuate the armature 163 or to hold said armature from operation by the series coil 166.

The valve piston 153 is provided with a land 171, intermediate its ends, which serves to close the passage of fluid from a passageway 172 to a passageway 173. Said last mentioned passageway is connected with a pipe 174 leading to the return through the valve casing 35, passageway 68, and return pipe 34. The passageway 172 is connected with the pipe 46 leading to the distributor valve 41. Fluid under pressure enters the valve 45 through the pipe 44 connected with a passageway 175 leading to the chamber of said valve. Drain passageways 176 and 177 are provided in said valve block and are connected with opposite ends of the chamber 154, to return any fluid which might leak by either end of said valve piston to the low pressure or tank side of the accumulator 15.

When the relief valve 45 is in the position shown in Figures 11 and 12, fluid under pressure from the variable pressure control valve 40 enters said valve through the pipe 44 and passage-

way 175. It then passes through the valve chamber 154, and out the passageway 172 and pipe 46, to the distributor valve 41.

When, however, the motors 10, 10 are over-loaded, the series coil 166 will move the armature 163 to the left. This will move the valve piston 153 to the left and will move the land 171 to a position to close the passage of fluid from the passageway 175 to the passageway 172, and to allow fluid to flow from the passageway 172 to the passageway 173, out the pipe 174, to return to the low pressure or tank side of the accumulator 15.

Upon the release of fluid under pressure from the line 46, when all of the ports in the distributor valve 41 leading to the pipes 103 to 108 inclusive are opened, the spring 100 will move the piston 96 in a direction, which in Figure 1 is shown as being towards the left, to successively close each port opening leading to each of said pipes, one by one, and permit fluid from said pipes to return to the tank through the drain 101. Said spring serves to move the piston 96 to the left, to successively open the pipes 108, 107, 106, 105, 104 and 103 to the return through the drain 101, and permit each associated contactor to open in a predetermined order. Said spring also tends to force fluid from the left-hand end of said distributor valve into the pipe 46 through the valve 30 45, to the return.

It may be seen from the foregoing that upon a predetermined load on the motors 10, 10, fluid will be released from the pressure line 46 and the contactors controlled by said distributor valve 35 will be opened in a predetermined order. It may also be seen that the arrangement of this valve and the connection of this valve in the fluid system is such as to prevent all of the contactors from opening at the same time, upon overload of the motor circuit, and thus prevent excessive arcing and burning of the contacts.

While I have herein shown and described one form in which my invention may be embodied, it will be understood that the construction thereof 45 and the arrangement of the various parts may be altered without departing from the spirit and scope thereof. Furthermore, I do not wish to be construed as limiting my invention to the specific embodiment illustrated, excepting as it may 50 be limited in the appended claims.

I claim as my invention:

1. In a fluid operating system, a plurality of fluid motors, an electric circuit controlled by said motors, a pump, a fluid storage tank, a distributor 55 valve, a high pressure line connecting said pump with said distributor valve, said distributor valve having a plurality of port openings therein, each of said port openings being connected with one of said motors for supplying fluid under pressure 60 from said high pressure line to said motors, for operating said motors in a predetermined sequence, a variable pressure control valve, a connection from said pump to said valve for supplying fluid under pressure thereto at a constant 65 pressure, a variable pressure control line connecting said control valve with said distributor valve, for supplying fluid under pressure to said distributor valve at pressures progressively increasing step by step, to operate said distributor valve and cause said distributor valve to open said port 70 openings to fluid under pressure in a predetermined sequence, and a relief valve operable upon a predetermined current load on said electric circuit and connected in said variable pressure control line between said variable pressure control 75

valve and said distributor valve, for relieving pressure from said control line leading to said distributor valve, to permit said distributor valve to successively close said port openings to fluid under pressure from said high pressure line and to open said port openings to the return upon a predetermined current load on said electric circuit.

2. In a fluid operating system, a plurality of fluid motors, an electric circuit controlled by said motors, a pump, a fluid storage tank, a distributor valve, a high pressure line connecting said pump with said distributor valve, said distributor valve having a plurality of port openings therein, each of said port openings being connected with one of said motors for supplying fluid under pressure from said high pressure line to said motors, for operating said motors in a predetermined sequence, a variable pressure control valve, a connection from said pump to said valve for supplying fluid under pressure thereto at a constant pressure, a variable pressure control line connecting said control valve with said distributor valve, for supplying fluid under pressure to said distributor valve at pressures progressively increasing step by step, to operate said distributor valve and cause said distributor valve to open said port openings to fluid under pressure in a predetermined sequence, and an electrically operated relief valve electrically connected with said electric circuit and connected in said variable pressure control line between said variable pressure control valve and said distributor valve, for relieving pressure from said control line leading to said distributor valve, to permit said distributor valve to successively close said port openings to fluid under pressure from said high pressure line and to open said port openings to the return upon a predetermined current load on said electric circuit.

3. In a fluid operated controller adapted to control an electric circuit, a plurality of electric contacts, a separate fluid motor for operating each of said contacts, a distributor valve for supplying fluid under pressure to said motors in a predetermined sequence, a variable pressure control valve for supplying fluid under pressure to said distributor valve, to cause said distributor valve to progressively open and successively supply fluid under pressure to said motors, and an electrically operated fluid relief valve, electrically connected with the electrical circuit, for by-passing pressure from said variable pressure control valve, upon a predetermined current load on said electric circuit.

4. In a fluid operated controller adapted to control an electric circuit, a plurality of electric contacts, a separate fluid motor for operating each of said contacts in a definite order, a distributor valve for supplying fluid under pressure to said motors in a predetermined order, a variable pressure control valve for supplying fluid under pressure to said distributor valve at pressures progressively increasing step by step, to cause said distributor valve to progressively open and supply fluid under pressure to said fluid pressure operating means, and an electrically operated fluid relief valve, electrically connected with said electrical circuit, and connected in the line from said variable pressure control valve to said distributor valve, for by-passing pressure between said variable pressure control valve and said distributor valve upon a predetermined current load on said electrical circuit.

5. In a fluid operated controller adapted to

control an electric circuit, a plurality of contacts for making and breaking an electric circuit, a separate fluid motor for operating each of said contacts in a definite order, a distributor valve having a plurality of port openings therein, each of said port openings being connected with one of said motors for supplying fluid under pressure to said motors in a predetermined order, a variable pressure control valve, a pressure line connecting said variable pressure control valve to said distributor valve for supplying fluid under pressure to said distributor valve at pressures progressively increasing step by step, to cause said distributor valve to progressively open said port openings to fluid under pressure, and an electrically operated fluid relief valve connected in said pressure line to relieve pressure from said pressure line upon a predetermined current load on said electric circuit.

6. In a fluid operated controller adapted to control an electric circuit, a plurality of contacts for making and breaking an electric circuit, a separate fluid motor for operating each of said contacts in a definite order, a distributor valve having a plurality of port openings therein, each of said port openings being connected with one of said motors for supplying fluid under pressure to said motors in a predetermined order, a variable pressure control valve, a pressure line connecting said variable pressure control valve to said distributor valve for supplying fluid under pressure to said distributor valve at pressures progressively increasing step by step, to cause said distributor valve to progressively open said port openings to fluid under pressure, an electrically operated fluid relief valve connected in said pressure line and electrical means for operating said valve, and electrical connections from said electric circuit to said relief valve to cause said valve to block the passage of fluid from said variable pressure control valve to said distributor valve and to release fluid pressure from said pressure line connected with said distributor valve, to permit said distributor valve to progressively close said port openings to pressure and permit the release of fluid pressure from said motors.

7. In a fluid operated controller adapted to control an electric circuit, a plurality of contacts for making and breaking an electric circuit, a separate fluid motor for operating each of said contacts in a definite order, a distributor valve having a plurality of port openings therein, each of said port openings being connected with one of said motors for supplying fluid under pressure to said motors in a predetermined order, a variable pressure control valve, a pressure line connecting said variable pressure control valve to said distributor valve for supplying fluid under pressure to said distributor valve at pressures progressively increasing step by step, to cause said distributor valve to progressively open said port openings to supply fluid under pressure to said fluid pressure operating means, an electrically operated fluid relief valve connected in said pressure line between said variable pressure control valve and said distributor valve, said relief valve being adapted to normally permit fluid to pass through said pressure line, but to stop the flow of fluid from said variable pressure control valve and to relieve fluid pressure from the pressure line to said distributor valve upon overload of said electric circuit, to permit said distributor valve to close said port openings to pressure and to open said port openings to the return.

8. In a fluid operated controller adapted to control an electric circuit, a plurality of contacts for making and breaking an electric circuit, a separate fluid motor for operating each of said contacts in a definite sequence, a distributor valve having a plurality of port openings therein, each of said port openings being connected with one of said motors for supplying fluid under pressure to said motors in a predetermined order, a variable pressure control valve, a pressure line connecting said variable pressure control valve to said distributor valve for supplying fluid under pressure to said distributor valve at pressures progressively increasing step by step, to cause said distributor valve to progressively open said port openings to supply fluid under pressure to said fluid pressure operating means, and an electrically operated fluid relief valve connected in said pressure line, said relief valve being adapted to permit fluid to pass through said pressure line when in one position, but to block the flow of fluid from said variable pressure control valve and to relieve fluid pressure from said distributor valve when in another position, an armature for operating said valve, and a series coil wound concentrically with said armature and connected in series with said electric circuit for moving said relief valve to a position to relieve fluid pressure from said distributor valve upon overload of said electric circuit, to permit said distributor valve to close said port openings to pressure, step by step, and open said port openings to the return.

9. In a fluid operated controller adapted to control an electric circuit, a plurality of contacts for making and breaking an electric circuit, a separate fluid motor for operating each of said contacts in a definite order, a distributor valve having a plurality of port openings therein, each of said port openings being connected with one of said motors for supplying fluid under pressure to said motors in a predetermined order, a variable pressure control valve, a pressure line connecting said variable pressure control valve to said distributor valve for supplying fluid under pressure to said distributor valve at pressures progressively increasing step by step, to cause said distributor valve to progressively open said port openings to supply fluid under pressure to said fluid motors in a definite sequence, an electrically operated fluid relief valve connected in said pressure line, said relief valve being adapted to permit fluid to pass through said pressure line when in one position, but to block the flow of fluid from said variable pressure control valve and to relieve fluid pressure from said distributor valve when in another position, an armature for operating said valve, a series coil wound concentrically with said armature and connected in series with said electric circuit for moving said relief valve to a position to relieve pressure from said distributor valve and permit said distributor valve to close said port openings to pressure step by step, and to open said port openings to the return upon a predetermined current load on said electric circuit, and a shunt coil wound concentrically with said armature and adapted to hold said valve in a closed position until said valve is manually reset by manually breaking the circuit to said shunt coil.

10. In a fluid operated controller adapted to control an electric circuit, a plurality of contacts for cutting a resistance out of or into said electric circuit step by step, a separate fluid motor connected with each of said contacts, a distributor valve for supplying fluid under pressure to said

motors in a predetermined order for operating each of said contacts in a definite sequence, said distributor valve including a valve piston and having a plurality of port openings, each of said port openings being connected with one of said motors, a variable pressure control valve for supplying fluid under pressure to said distributor valve at progressively increasing pressures, to move said distributor valve piston to uncover said port openings to fluid under pressure step by step, a spring for moving said distributor valve piston in a direction to close said port openings to fluid under pressure and to open said port openings to the return, an electrically operated fluid relief valve, a pressure line connecting said variable pressure control valve with said fluid relief valve, a pressure line connecting said fluid relief valve to said distributor valve, and means connected in said electrical circuit for closing said fluid relief valve to pressure from said pressure control valve and opening said valve to permit fluid in said pressure line connecting said relief valve to said distributor valve, to flow to the return, and to permit said distributor valve spring to move said piston in a direction to progressively close said port openings to pressure, and to open said port openings to the return.

11. In a fluid operated controller adapted to control an electric circuit, a plurality of contacts for cutting a resistance out of or into said electric circuit step by step, a separate fluid motor operatively connected with each of said contacts for operating each of said contacts in a definite sequence, a distributor valve for supplying fluid under pressure to said motors in a predetermined order, said distributor valve including a valve piston and having a plurality of port openings, each of said port openings being connected with one of said motors, a variable pressure control valve for supplying fluid under pressure to said distributor valve at progressively increasing pressures, to move said distributor valve piston to uncover said port openings to fluid under pressure step by step, a spring for moving said distributor valve piston in a direction to close said port openings to fluid under pressure and to open said port openings to the return, an electrically operated fluid relief valve, a pressure line connecting said variable pressure control valve with said fluid relief valve, a pressure line connecting said fluid relief valve to said distributor valve, and means connected in said electrical circuit for closing said fluid relief valve to pressure from said pressure control valve and opening said valve to permit fluid in said pressure line connecting said relief valve to said distributor valve, to flow to the return, and to permit said distributor valve spring to move said piston in a direction to progressively close said port openings to pressure, and to open said port openings to the return.

12. In a fluid operated controller adapted to control an electric circuit, a plurality of contacts for cutting a resistance out of or into said electric circuit step by step, a separate fluid motor operatively connected with each of said contacts, for operating each of said contacts in a definite sequence, a distributor valve for supplying fluid under pressure to said motors in a predetermined order, said distributor valve including a piston,

a plurality of port openings, each of said port openings being connected with one of said motors, a variable pressure control valve for supplying fluid under pressure to said distributor valve at progressively increasing pressures, to move said distributor valve piston to uncover said port openings to fluid under pressure step by step, a spring for moving said distributor valve piston in a direction to close said port openings to fluid under pressure and to open said port openings to the return, an electrically operated fluid relief valve, a pressure line connecting said variable pressure control valve with said fluid relief valve, a pressure line connecting said fluid relief valve to said distributor valve, means connected in said electrical circuit for closing said fluid relief valve to pressure from said pressure control valve and opening said valve to permit fluid in said pressure line connecting said relief valve to said distributor valve, to flow to the return, and to permit said distributor valve spring to move said distributor valve piston in a direction to progressively close said port openings to

pressure and to connect said port openings to the return, including an armature operatively connected with said relief valve, a series coil wound concentrically with said armature and connected in series with said electric circuit, for operating said relief valve upon overload of said electric circuit, and a shunt coil wound concentrically with said armature and adapted to hold said valve in a closed position until said valve is reset manually by interrupting the circuit to said shunt coil under manual control.
